UNITED STATES PATENT OFFICE.

HALBERT E. SMITH, OF SEIBERT, COLORADO.

TRAIN-PIPE COUPLING.

1,184,216.

Specification of Letters Patent.

Patented May 23, 1916.

Application filed April 2, 1915. Serial No. 18,782.

To all whom it may concern:

Be it known that I, HALBERT E. SMITH, a citizen of the United States, residing at Seibert, in the county of Kit Carson and State of Colorado, have invented certain new and useful Improvements in Train-Pipe Couplings; and I do hereby declare the following to be a full, clear, and exact description of the invention, such as will enable others skilled in the art to which it appertains to make and use the same.

This invention relates to improvements in pipe couplings especially designed for connecting the air pipes upon railway cars.

The invention has for its object to provide a train pipe coupling of simple and efficient construction including a novel type of joint, whereby a limited lateral swinging movement of the free ends of the coupling is permitted, thereby facilitating relative movement of the adjacent ends of cars of a train.

Another object is the provision of a simple and efficient guard or protective housing for the coupling designed to prevent injury to the coupling during traveling of the train.

With these and other objects in view, the invention consists in the novel construction, arrangement and formation of parts as will be hereinafter specifically described, claimed and illustrated in the accompanying drawing, in which:

Figure 1 represents a side elevation of the coupling, partly broken away, illustrating a fragment of a railway car. Fig. 2 represents a fragmentary longitudinal sectional view through the coupling. Fig. 3 represents a fragmental detail view of one of the coupling elements removed. Fig. 4 represents a horizontal sectional view on the line 4-4 of Fig. 1. Fig. 5 represents a detail sectional view on the line 5-5 of Fig. 1, and Fig. 6 represents a fragmental detail view of the valve in the coupling pipe.

Referring to the drawing in detail, where-in similar reference numerals designate corresponding parts throughout the several views, the numeral 8 indicates the main air pipe which is connected at each end of the car with a horizontally disposed cylinder 9 rigidly secured beneath the car and stationary relative thereto. A longitudinally slid- able coupling pipe 10 is slidably mounted through the outer head 11 of each cylinder 9, projects into the latter and is normally retained in outwardly extended position by the tension of a spring 12 engaged at one

end with the inner end of the cylinder and at the opposite end with the flanged extremity 13 of the slidable coupling pipe 10. A substantially C shaped pipe 14 is connected at its central or web portion in the outer extremity of the coupling pipe 10 and the spaced vertically alined free ends 15 thereof are pivotally connected with the hollow head 16 of the coupling pipe 17 movable upon a vertical axis. A suitable type of valve 18 is arranged in the slidable coupling pipe 10 intermediate the flange 13 and joint pipe 14 for controlling the passage of fluid through the coupling pipe and operable by a rod 19 extended laterally of the car, which latter is designated generally by the numeral 20.

A hanger designated generally by the numeral 21 for supporting the slidable coupling pipe 10 and C pipe 14 includes a track 22 suitably secured to the car 20, and a roller 23 movable longitudinally upon the track 22 and connected with the upper vertical member of the C shaped pipe 14 by a bracket 24.

A hollow tubular plunger 25 is slidably mounted within and projects a distance outwardly of the outer end of the pivoted coupling pipe 17 and is provided with a flared inner end 26 snugly fitting within said pivoted pipe 17. The plunger 25 is normally retained in outwardly extended position by the tension of a spring 27 engaged at its outer end with the inner flared extremity 26 of the slidable plunger 25 and at its opposite end with an annular flange 28 formed adjacent the inner extremity of the pivoted pipe 17. A pair of gaskets 29 having peripheral grooves are positioned upon the plunger 25 and are slidable thereon and receive the angular flanges 30 and 31 of the plunger 25 and a coupling sleeve 32, respectively. An annular sealing cushion or gasket 33, formed of rubber or other suitable material, is removably secured in the outer end of the sleeve 32 and is provided with an outwardly directed flange 34 overlying the end of the sleeve 32 and adapted to engage the corresponding flange of the coupling member at the adjacent end of the adjacent car so as to provide an air tight coupling between the hollow plungers 25 in the coupling members at the adjacent ends of the cars.

Frusto-conical guards 36 are secured at their small ends to the pivoted coupling

pipes 17 and are adapted to engage each other at their relatively large ends, as illustrated in Figs. 1 and 2 when the cars are coupled. The guards 36 are retained closed or connected by a spring latch member 37, which is adapted to automatically disengage or release when the cars are uncoupled.

What I claim is:

1. A train pipe coupling comprising an inner slidable pipe, an outer pipe pivotally secured to the slidable pipe, and a spring actuated coupling member carried by the pivoted pipe.

2. A train pipe coupling including an inner slidable pipe, means normally retaining said slidable pipe in outwardly extended position, an outer pipe pivotally secured to the inner slidable pipe, and a coupling member slidably secured to the pivoted pipe.

3. A train pipe coupling comprising an inner slidable pipe, an outer pipe pivotally secured to the inner pipe, a plunger slidably mounted in the pivoted pipe, and a coupling member carried by said plunger.

4. A train pipe coupling comprising an inner slidable pipe, an outer pipe pivotally secured to the inner slidable pipe, a hollow plunger slidably mounted in the pivoted pipe, means normally retaining said plunger in outwardly extended position, and a coupling member carried by said plunger.

5. A train pipe coupling comprising an inner slidable pipe, means normally retaining said pipe in outwardly extended posi-

tion, an outer pipe pivotally secured to the inner slidable pipe, a hollow plunger slidably mounted in the pivoted pipe, means normally retaining said plunger in outwardly extended position, and a coupling member carried by said hollow plunger.

6. A train pipe coupling including a slid-
able pipe, a pipe pivotally secured to said
slidable pipe, a hollow plunger slidably
mounted in the pivoted pipe, a coupling
member at the outer end of the hollow plun-
ger, means normally retaining said plunger
in outwardly extended position, and a frusto-
conical guard rigidly secured to the pivoted
pipe and movable therewith.

7. A train pipe coupling including a slid-
able pipe, a pipe pivotally secured to said
slidable pipe, a coupling member carried by
said pivoted pipe, a frusto-conical guard
member secured at its small end to said piv-
oted pipe, and a spring latch carried by
said guard.

8. In a train pipe coupling, a slid-
able pipe, a substantially C shaped pipe con-
nected centrally with said slidable pipe and
having upon ends, a T shaped pipe having
the head pivotally secured in the open
ends of the C shaped pipe, and a coupling
member carried by said T shaped pipe.

In testimony whereof I affix my signature in presence of two witnesses.

HALBERT E. SMITH.
